UNITED STATES PATENT OFFICE.

WILLIAM O. MILLER, OF BILLINGS, MONTANA.

ROTARY INTERNAL-COMBUSTION ENGINE.

1,106,666.

Specification of Letters Patent. Patented Aug. 11, 1914.

Application filed September 19, 1912. Serial No. 721,254.

To all whom it may concern:

Be it known that I, WILLIAM O. MILLER, a citizen of the United States, residing at Billings, in the county of Yellowstone and 5 State of Montana, have invented certain new and useful Improvements in Rotary Internal-Combustion Engines, of which the following is a specification, reference being had therein to the accompanying drawing.

10 My invention relates to internal combustion engines in which a plurality of like pistons are constantly driven in an annular piston chamber or cylinder by rapidly recurring explosions in the rear of each, mutilated cylinder heads rotating continuously 15 in planes intersecting said chamber serving to close the latter at proper times in front and rear of the several pistons, thus dividing the chamber into what are the equivalent of 20 short cylinders of different lengths. The charges are compressed by the pistons and then passed from front to rear of the same and immediately exploded, no explosions occurring simultaneously, however.

25 The main features of the invention may be embodied in an engine in which explosions are caused by any of the ordinary forms of ignition devices, but preferably the engine is made in such manner that explosions 30 may be caused either by special ignition devices or by ignition through heat generated, partly at least, by very high compression which is nearly instantaneous. For illustration, the invention is shown as embodied 35 in an engine having four quadrantly arranged pistons, each at short intervals compressing in its front a charge which then passes to its rear and is there immediately exploded. In the devices shown, this 40 operation occurs three times during each revolution of each piston, or twelve times during each rotation of the common power shaft which carries all the pistons.

In the accompanying drawings, Figure 1 45 is a medial section in the plane of the piston chamber. Fig. 2 is a section on the line 2—2, Fig. 1. Fig. 3 is a section on the line 3—3, Fig. 2. Fig. 4 is a section on the line 4—4, Fig. 1. Fig. 5 is a side view of one 50 of the cylinder-head plates.

In these figures, which are partly dia- 55 grammatic, A, A' represent casing halves provided with central openings to receive a power shaft B and with annular recesses, concentric with the shaft and adapted to form, when the halves are bolted together, a

laterally closed circular piston chamber C with which communicate a series of inlet 60 passages D, exhaust ports E and by-passes F. This main casing is further provided with nine rigidly connected, two-part casings, G, G', G², for rotary cylinder heads all lying in planes which are radial with respect to the power shaft and which are peripherally cut away so that in rotating they al- 65 ternately obstruct and cease to obstruct the piston chamber.

Between the halves of the main casing closely fits a disk H fixed to the power shaft and carrying at its margin thin quadrantally spaced like pistons H', H², H³, H⁴, closely fitting the piston chamber. The latter communicates, at three angularly equidistant points, and by means of passages F', F² with the three by-passes, respectively. 70 These two passages are so arranged that each passing piston will close them in succession and open them in succession but cannot close both at the same time. Adjacent to each by-pass, and on opposite sides there- 75 of, respectively, are two of the cylinder head casings, G, G' in which fit, respectively, cylinder head plates I, I', fixed to shafts J which pass centrally through the corresponding casings and are constantly rotated 80 in any suitable way, as by gears K, K'. 85

At some distance in advance of the plates just mentioned (considered with respect to the direction of travel of the pistons) is an analogous cylinder head I² mounted like 90 those already mentioned and rotated in a similar way. Slightly in advance of each of these members I² is a preferably valve-controlled intake opening D and in the rear of each is an exhaust port E. That the same 95 engine may be operated either by special igniting devices or by sudden high compression, I provide near the passage F' an inlet M through which certain crude oils may be forcibly injected by devices not shown, and also provide near the same point a suitable 100 ignition device N, which may be used or not as may be desired, this usually depending upon the kind of fuel to be used for the time being.

105 Each cylinder head plate is a plane disk extending inward to the inner side of the piston chamber but having its peripheral portion cut away through a certain angular distance and to a depth equal to the diameter 110 of said chamber so that as the disk rotates it completely cuts off that chamber, thus form-

ing a sort of cylinder head, and then while the cut away portion is passing leaves the chamber unobstructed. The rotation is such that each plate passes out of obstructing position as each piston approaches and cuts off the chamber in the rear of each piston after it has passed. The peripheral extent of the cutting depends upon the office of the plate or cylinder head.

10 Supposing that the sparking device is to be used and that the movement of the pistons is clockwise, each cylinder head on leaving an inlet opening, the cylinder head or plate in its rear having closed, draws in a charge (see piston H³) and at the same time compresses in its front a charge drawn in in the rear of the preceding piston. Meantime, the cylinder head on the far side of the next of the by-passes closes and the cylinder head on the near side opens, allowing the piston to pass and then immediately closes behind it. The charge is then highly compressed by the advancing piston and forced through the passage F² (Fig. 1, piston H') into the by-pass, which is made as a small chamber. The further advance of the piston closes the passage F' and opens the passage F², allowing the charge to pass to the rear of the piston and fill the space between it and the next cylinder head in the rear. At this moment a spark ignites the charge and the piston receives a forward impulse. At just the proper instant, the cylinder head next in front of the piston moves out of the path of the piston and the next cylinder head in advance closes, so that the advancing piston forces out at the next exhaust passage any gases that may be in its front, the last mentioned cylinder head opening in time to allow the piston to pass. In passing through the next third of its circular path the piston and corresponding parts repeat this entire operation; and so for each of the pistons in succession, but as the number of by-passes is not the same as the number of pistons, no two ever perform the same function simultaneously, two being at different stages of compressing and one pushing out products of combustion at the time of explosion in the rear of the fourth piston.

In case no ignition devices are used, the proper kind of oil is injected under high pressure and only air is drawn in at the intake ports.

55 It may also be observed, that the construction gives nearly perfect balancing of parts so that at high speed there is practically little vibration or undesirable strain on any part, nor is there the usual necessity for 60 the use of a fly-wheel. The construction gives, in effect, a series of independent short cylinders varying in length according to the work of each, and all reciprocating parts and all valves except only 65 hand valves outside the engine, for con-

trolling the supply pipes, are avoided. It should be still further noted that packing rings and the like are used wherever necessary, such packings being shown at Q and R, the latter packings being rings, preferably of metal, wider than the spaces in which the rotary plates I work, so that the pistons safely pass those spaces.

What I claim is:

1. The combination with an annular piston chamber having a by-pass, of a piston traveling in said chamber and forming the sole means for opening and closing said by-pass, means for closing said piston chamber slightly in advance of said by-pass as the piston approaches the point of closure, whereby a charge is compressed and forced into the by-pass by the advancing piston, means for closing the chamber on the rear side of the by-pass and piston before the latter passes the rear end of the by-pass, and means for exploding the charge after the piston has opened the rear end of the by-pass and while it covers the front end.

2. The combination with a power shaft 90 bearing a series of pistons and a casing having an annular piston chamber concentric with the power shaft and a series of valveless by-passes each slightly longer than each piston, of means for temporarily closing said chamber slightly in advance of each by-pass as a piston approaches that by-pass, means for temporarily closing said chamber upon the rear side of the same by-pass after the piston passes that point of closure and 100 before it passes the rear end of the same by-pass, and means for exploding the charge after said rear end is uncovered by the piston.

3. The combination with an annular piston chamber having a valveless by-pass and exhaust and inlet ports in the front and rear, respectively, of the by-pass, of a piston traveling in said chamber and adapted to close the ends of the by-pass in succession only, as it passes them, means for closing the chamber temporarily slightly in advance of the forward end of the by-pass as the piston approaches this point of closure, means for closing the chamber temporarily in the 115 rear of the by-pass after the piston has passed this second point of closure, means for igniting the charge when the piston has opened the rear end of the bypass and obstructs the front end of the same, and means 120 for closing the chamber slightly in advance of said exhaust port while the piston is approaching this third point of closure under the impulse of the explosion.

4. The combination with an annular piston chamber having a series of equally spaced valveless by-passes with an inlet port in the rear of each and an exhaust port in advance of each, a numerically different series of equally spaced pistons traveling 125

in said chamber and each adapted to close the rear and forward ends of each by-pass in succession only, means for closing the chamber momentarily slightly in advance of each by-pass when any piston approaches it from the corresponding inlet port, means for closing the chamber momentarily in the rear of the same by-pass after the piston has passed this point of closure, means for igniting the charge when the piston has opened the rear end of the same by-pass and is obstructing the forward end of the same, and means for momentarily closing the chamber slightly in advance of the corresponding 10 exhaust port while the piston is nearing the latter.

5. In apparatus of the class described, the combination with a casing having an annular piston chamber provided with a valveless by-pass from one point to another thereof, of a piston traveling in said chamber and incapable of closing both terminals of said by-pass simultaneously, and means for temporarily closing said chamber at points in 20 front and rear of said by-pass while the piston is between said points of closure.

6. The combination with a casing having an annular piston chamber provided at regular intervals with valveless by-passes from 25 one point to another thereof, of a series of pistons differing in number from the by-passes and incapable of covering at once both terminals of any by-pass, and mutilated disks rotating in radial planes for closing the chamber on each side of each by-pass while a piston is moving between the points of closure and a charge is forced through the by-pass from front to rear of the piston by the latter.

40 7. The combination with a casing having an annular piston chamber and provided with a series of spaced valveless by-passes and with a corresponding series of inlet and exhaust ports at some distance in advance 45 of the by-passes, respectively, rotating

plates arranged to close the chamber momentarily in front and rear of each by-pass, similar plates arranged to then momentarily close the chamber between the inlet and exhaust ports next in advance, and a numerically different series of pistons traveling in 50 said chamber, the movements of the plates being timed to close the chamber on each side of each by-pass while a piston between the points of closure pushes a charge 55 through the by-pass from its own front to its rear and to close it at a more advanced point while the same piston pushes out products of combustion and a preceding piston draws in a charge. 60

8. The combination with a casing having an annular piston chamber provided with series of spaced by-passes, inlet ports, and exhaust ports, of a series of pistons traveling in said chamber and forming the sole 65 means for opening and closing the by-passes, and a series of rotary plates closing the chamber momentarily, in front and rear of each piston, said plates being timed to intake of fuel behind each piston, compression of fuel in front of each piston, and expulsion of gases by each piston, as each moves from one by-pass to a point beyond the next by-pass in advance. 70

9. The combination with a casing having 75 an annular piston chamber provided at intervals with inlet ports, exhaust ports and by-passes, of a numerically different series of pistons traveling in said chamber, forming the sole means for controlling the by-passes and each arranged to compress a charge drawn in by the next piston in advance and force out burned gases left in the rear of the said preceding piston. 80

In testimony whereof I affix my signature 85 in presence of two witnesses.
